UNITED STATES PATENT OFFICE.

FREDERICK S. HUNT, OF MILWAUKEE, WISCONSIN, ASSIGNOR TO MILWAUKEE DUST-LESS BRUSH COMPANY, OF MILWAUKEE, WISCONSIN, A CORPORATION OF WISCONSIN.

DUSTLESS BRUSH.

Application filed September 10, 1923. Serial No. 661,948.

To all whom it may concern:

Be it known that I, FREDERICK S. HUNT, a citizen of the United States, and resident of Milwaukee, in the county of Milwaukee, and State of Wisconsin, have invented new and useful Improvements in Dustless Brushes, of which the following is a description, reference being had to the accompanying drawings which are a part of this specification.

This invention relates to improvements in dustless brushes.

In brushes of the dustless type, the back or body of the brush is usually provided with an oil reservoir and a series of absorbent and non-absorbent tufts, the latter being surrounded by the former and connected to the reservoir to supply minute quantities of volatile oil to the surface being cleaned. As thus usually constructed, the absorbent tufts, which extend through openings in the wooden brush back, tend to swell and stop the desired flow of oil and if less tuft strands are placed in the openings or the openings enlarged, the flow of oil will be too great.

It is one of the objects of the present invention to overcome the before mentioned objectionable features and provide a dustless brush in which the absorbent tufts are mounted in a manner to provide a predetermined flow of oil without liability of the flow being retarded.

A further object of the invention is to provide a dustless brush in which the absorbent tufts are mounted in metal tubes and are reinforced by non-absorbent tuft strands arranged in a manner to permit the feed of oil to the surface being cleaned.

A further object of the invention is to provide a dustless brush which is of simple construction, is strong and durable, and is well adapted for the purpose described.

With the above and other objects in view, the invention consists of the improved dustless brush and its parts and combinations as set forth in the claims, and all equivalents thereof.

In the accompanying drawing, in which the same reference characters indicate the same parts in all of the views:

Fig. 1 is a front view of the improved dustless brush, a part being shown in section to show interior construction;

Fig. 2 is a transverse sectional view thereof on a larger scale;

Fig. 3 is a sectional detail view of one of the absorbent tufts and a portion of the brush back taken on a still larger scale; and

Fig. 4 is a sectional detail view of one of the absorbent tufts.

Referring to the drawing, the numeral 5 indicates the brush back provided with a series of outer perforations for receiving non-absorbent tufts or bristles 6 which may be fastened to the back in any manner desired. A metal plate 7 extends over the upper surface of the back 5 and in connection with the cover 8 spaced therefrom, forms a reservoir 9 for holding kerosene or other volatile oil adapted to be used in sweeping. The cover 8 is formed with a continuous groove 10 to engage the edge portions of the back 5 to form a tight closure therewith and with the edge portions of the plate 7 as shown in Fig. 2. To seal the joint between the plate edges and the grooved portion 10, cement 11 is interposed therebetween. The said back 5 is formed with a medial longitudinal line of perforations 12 for receiving tubular metal members or ferrules 13 having annular flanges 13' at their lower ends. The upper ends of the tubular members also extend through aligned perforations 14 formed in the plate 7 and are flanged over and soldered as indicated by the numeral 15 to form an oil tight joint.

Absorbent tuft strands or bristles like palma fiber 15 are mixed with non-absorbent bristles like horse hair 16 and the combined strands are inserted into the tubular members 13 and are held in position by wires 17.

It has been found in practice that in using the absorbent strands alone, when saturated with oil, they swell and fill up all of the interstices between the strands and retard or stop the feed of oil, whereas by mixing non-absorbent strands or bristles like horse hair, the interstices between the bristles remain open and the absorbent bristles are not compressed to an extent to stop the flow of oil therethrough, with the result that a constant feed of oil is maintained. The oil so fed will flow downwardly to the lower ends of the bristles and contact with the dust on the surface being cleaned and will prevent the rising of said dust. The use of horse hair or other like bristles

or tuft strands also serves to reinforce the absorbent strands and maintain them in position.

An opening covered with a cap 17' is provided for filling the reservoir 9 with oil. A handle 18 adjustably connected to the back 5 is also provided for using the brush.

From the foregoing description it will be seen that the dustless brush provides an 10 all metal reservoir for holding and feeding the oil to the oil tufts and that the said tufts assure a constant feed of oil to the tufts when the brush is in sweeping position.

What I claim as my invention is:

15 1. A dustless brush, comprising a brush back having an oil reservoir provided with a plurality of tuft openings, and a tuft composed of absorbent and non-absorbent strands extending into each of said openings 20 to control the flow of oil therethrough.

2. A dustless brush, comprising a brush back having a plurality of tuft openings, an oil reservoir forming part of said brush back and having a plurality of tubular portions which extend through some of the 25 brush back openings, a tuft composed of mixed absorbent and non-absorbent strands extending into the tubular portions, and non-absorbent tufts extending into the other 30 openings of the brush back.

3. A dustless brush, comprising a brush back having a plurality of tuft openings, a metal plate extending over the upper surface of the back and having openings in 35 register with some of the back openings,

tubular members extending through the registering openings and having means for connection with the metal plate, a cover having a grooved portion which extends around and overlaps the edge portions of the brush 40 back and the metal plate to form a reservoir in connection with said plate, absorbent tuft strands extending into the tubular members, and non-absorbent tufts extending into the brush back openings. 45

4. A dustless brush, comprising a brush back having a plurality of tuft openings, a metal plate extending over the upper surface of the back and having openings in register with some of the back openings, tubular 50 members extending through the registering openings and having flanges at their upper and lower ends which engage the plate and the bottom portion of the brush back, a cover engaging the edge portions of the 55 brush back and the metal plate to form a reservoir in connection with said plate, tufts composed of absorbent and non-absorbent strands extending into the tubular members, and non-absorbent tufts extending into the 60 brush back openings.

5. A tuft for a dustless brush, comprising a tubular member, and absorbent and non-absorbent tuft strands extending into said 65 tubular member to control the flow of oil therethrough.

In testimony whereof, I affix my signature.

FREDERICK S. HUNT.
